(57) **CLAIM**

The ornamental design for a helmet stand, as shown and described.

DESCRIPTION

FIG. 1 is a top plan view of a helmet stand showing my new design;

FIG. 2 is a front elevational view thereof;

FIG. 3 is a bottom plan view thereof;

FIG. 4 is a rear elevational view thereof;

FIG. 5 is a right side elevational view thereof;

FIG. 6 is a sectional view taken along line 6—6 of FIG. 1;

FIG. 7 is a sectional view taken along line 7—7 of FIG. 1;

FIG. 8 is a sectional view taken along line 8—8 of FIG. 1;

FIG. 9 is a sectional view taken along line 9—9 of FIG. 1;

FIG. 10 is a sectional view taken along line 10—10 of FIG. 1;

FIG. 11 is a sectional view taken along line 11—11 of FIG. 1;

FIG. 12 is a perspective view of the helmet stand; and,

FIG. 13 is a perspective view thereof showing a state of being used.

A left side elevational view of the helmet stand is shown symmetrically with the right side elevational view shown in FIG. 5 and therefore the left side elevational view is omitted. The broken lines shown in FIG. 13 are for illustrative purposes only and form no part of the claimed design.
